CLAIM

The ornamental design for a sandal, as shown and described.

DESCRIPTION

FIG. 1 is a right side view showing my design;

FIG. 2 is a left side view thereof;

FIG. 3 is a top perspective view thereof;

FIG. 4 is a rear view thereof;

FIG. 5 is a front view thereof;

FIG. 6 is a top view thereof; and,

FIG. 7 is a bottom view thereof.

The broken lines showing portions of the sandal sole in the drawings shows unclaimed subject matter.
